CLAIM

The ornamental design for a disposable airway adapter for respiratory gas monitoring, as shown and described.

DESCRIPTION

FIG. 1 is a perspective view showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the figures are included for the purpose of illustrating portions of the disposable airway adapter for respiratory gas monitoring and form no part of the claimed design.

1 Claim, 6 Drawing Sheets
